UNITED STATES PATENT OFFICE.

WERNER SCHMID, OF BROOKLYN, NEW YORK, ASSIGNOR TO NATIONAL LACE AND EMBROIDERY COMPANY, OF NEW YORK, N. Y.; A CORPORATION OF NEW YORK.

DESIGN FOR A DOILY.

Application filed March 6, 1925. Serial No. 12,617. Term of patent 3½ years.

To all whom it may concern:

Be it known that I, WERNER SCHMID, a citizen of the United States, residing in the borough of Brooklyn of the city of New York, in the State of New York, have invented a new, original, and ornamental Design for a Doily, of which the following is a specification, reference being had to the accompanying drawing, forming a part hereof, which shows a plan view of a doily embodying the new design, each of the four fields being identical with the complete field shown in the upper portion of the drawing.

I claim the ornamental design for a doily as shown.

This specification signed this 3d day of March A. D. 1925.

WERNER SCHMID.
